(57) CLAIM

The ornamental design for a combined food and beverage container, as shown and described.

DESCRIPTION

FIG. 1 is a perspective view of a combined food and beverage container, showing my design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

The broken line showing in the Figures represents portions of the combined food and beverage container and forms no part of the claimed design.
